SHADOW BOX

Louis A. Papas, 1727 N. Rutherford Ave., Chicago, Ill.

Filed Aug. 5, 1957, Ser. No. 676,318

6 Claims. (Cl. 229—34)

This invention relates to a shadow box and more particularly to a shadow box which can be assembled from a sheet material blank without the use of any auxiliary fastening members.

Heretofore conventional shadow boxes made of wood and similar permanent materials have been used in the home to attractively display objects of art and conversation pieces. More recently their use commercially to display articles and advertising pieces in stores and display areas has become desirable. Heretofore the more universal adoption thereof has been limited by various objectionable features. Thus, because advertising displays are frequently changed, expensive storage space was required to store the shadow boxes until they were again required. Although it was true that some of these shadow boxes could be disassembled after use, this disassembly required the time and services of skilled employees. In addition, the parts and fastening members were often misplaced and were not always readily available when the shadow box had to be reassembled. What is needed, therefore, and comprises the chief object of this invention is a shadow box which is so inexpensive that it can economically be thrown away after use.

Still another object of this invention is to provide a shadow box which is formed entirely of sheet material and which can be assembled without the use of auxiliary fasteners.

Still another object of this invention is to provide a shadow box which can be assembled and disassembled without the use of skilled labor.

Yet another object of this invention is to provide a throw-away shadow box which is formed entirely from a single cardboard blank and which is strong enough to support heavy articles for display.

A further object of this invention is to provide a shadow box which can be made very inexpensively and quickly.

Yet a further object of this invention is to provide a shadow box which is simple to assemble and attractive in appearance.

With the foregoing and other objects in view which will appear as the description proceeds, the invention consists of certain novel features of construction, arrangement and a combination of parts hereinafter fully described, illustrated in the accompanying drawings, and particularly pointed out in the appended claims, it being understood that various changes in the form, proportion, size and minor details of the structure may be made without departing from the spirit or sacrificing any of the advantages of the invention.

For the purpose of facilitating an understanding of my invention, I have illustrated in the accompanying drawings preferred embodiment thereof, from an inspection of which, when considered in connection with the following description, my invention, its mode of construction, assembly and operation, and many of its advantages should be readily understood and appreciated.

Referring to the drawings in which the same charac-

2

ters of reference are employed to indicate corresponding or similar parts throughout the several figures of the drawings:

Fig. 1 is a perspective view of the assembled shadow box;

Fig. 2 is a sectional view of the shadow box taken on the line 2—2 of Fig. 1;

Fig. 3 is a sectional view taken on the line 3—3 of Fig. 1;

Fig. 4 is a sectional view taken on the line 4—4 of Fig. 2;

Fig. 5 is a plan view of the blank which is employed in the manufacture of the shadow box embodying this invention;

Fig. 6 is a perspective view of a corner of the shadow box showing the initial steps in its assembly;

Fig. 7 is a perspective view of a corner of the shadow box showing the next step in its assembly;

Fig. 8 is a perspective view of a corner of the shadow box showing the third step in its assembly;

Fig. 9 is a perspective view of a corner of the shadow box showing the fourth step in its assembly;

Fig. 10 is a perspective view of the shadow box showing the fifth step in its assembly;

Fig. 11 is a perspective view of the shadow box showing the sixth step in its assembly;

Fig. 12 is a perspective view of the shadow box showing the seventh step in its assembly;

Fig. 13 is a perspective view of the shadow box showing the final step in its assembly.

Referring now to Fig. 1 of the drawings, the shadow display box indicated generally by the reference numeral 10 comprises a rectangular back wall 12 and integrally formed rectangular side and end walls 14 and 16. These side and end walls are disposed perpendicularly to the back wall and terminate in integral side and end trapezoidal-shaped frame members 18 and 20. These frame members, as seen in Figs. 2 and 3, are bent inwardly toward the back wall at an obtuse angle to the plane of the side and end walls but are spaced from said back wall.

The entire shadow display box is formed from a single cardboard or sheet material blank, see Fig. 5. For purposes of convenience the fold or crease lines in the blank have been illustrated as double lines while the cut lines 45 are shown as single lines. This blank comprises the centrally positioned rectangular back wall section 12. The rectangular side and end wall sections 14 and 16 are integral with the edges of the back wall section, and these in the assembled shadow box form the side and end walls. These sections are separated from the back wall section 12 by score or crease lines 15 and 17. The opposite edges of wall sections 14, remote from back wall 12, are integrally connected with first, second and third rectangular sections 22, 24 and 26 which are themselves separated by score lines 21, 25 and 27. Sections 22, 24 and 26, as seen in Fig. 2, are adapted to be folded on the score lines to form the side frame members 18. Similarly the opposite edges of the end section 16 remote from the back wall 12 are integrally connected to 50 a first trapezoidal-shaped section 28 and to second and third rectangular sections 30 and 32. These sections are separated by the score lines 29, 31 and 33. Sections 28, 30 and 32, as seen in Fig. 3 are adapted to be folded on their score lines to form the end frame members 20.

60 In order to hold the shadow box in its assembled shape without the use of auxiliary fasteners, the blank is also provided with substantially rectangular reinforcing and holding members 34. The reinforcing members 34 are integral with the opposite sides of the side walls 14 and are separated from it by score lines 35. Each reinforcing member is provided with a locking tab 36 which is integrally secured to the reinforcing members by score

line 37. In addition, a mounting flange 38 is integrally secured to the reinforcing member 34 by score lines 39. When the shadow display box is assembled, the reinforcing members are bent to coincide with the opposite sides of the inner surfaces of the end walls 16 to reinforce it, and the mounting flanges 38 are then adapted to be bent perpendicularly, see Fig. 4. These mounting flanges are provided with aligned openings 40, see Fig. 1, which are adapted to receive various devices such as mounting rods or fluorescent lights.

In assembled position, edge 42 of the reinforcing member is parallel to back wall 12, and this edge is provided with a triangular recess 44, see Fig. 6. This recess has a stop edge 46 which will then be perpendicular to the back wall 12. Edge 46 is adapted to be engaged by an aligning tab 48, which as seen in Fig. 5 is integrally secured to the opposite edges of section 22. This stop tab 48 is adapted to engage the stop edge 46 when the side walls 14 are exactly perpendicular to the back wall 12. Accordingly, it provides a convenient aligning means for holding the side and end walls of the shadow box perpendicular to the back wall 12 and for keeping uniform the obtuse angle the frame members make with the side and end walls. In addition, when the shadow box is assembled, the locking tab 36 is adapted to be bent on the score line 37 perpendicular to the reinforcing member 34 for purposes described below.

On the opposite edges of the second section 24 are integral substantially rectangular locking flanges or members 50. These flanges are separated from section 24 by score lines such as 51 and terminate in three integral fingers such as 52. These fingers are connected to the locking flange by score lines 53. The center finger 55 is bent back when the shadow box is assembled, and this finger is adapted to be embraced by the locking tab 36 in interlocking engagement, see Figs. 1 and 6. The edge 54 of the remaining fingers 52 of the locking flange 50 bears against the corner edge 56 of the back wall 12 when the frame members 18 are properly positioned and provides thereby an additional aligning means, and with the locking tab 36 embracing the center finger 55 as described above, the side frame members 18 are held in this position.

Locking members 58 are provided for holding the end frame members 20 in place. These locking members are rectangular in shape and are integrally connected to the opposite ends of the second section 30 by score lines 59. The locking member itself comprises two substantially square sections 60 and 62 which are separated by a score line 61. When the box is assembled, section 60 embraces the bottom section 24 of the frame member 18, while section 62 bears against the inner surface of side wall 14 with edge 64 bearing against the edge 66 of the bottom wall 12, see Figs. 12 and 13. When this is done display flanges 20 will be tightly locked in overlapping position against the edges of the display flanges 18 and the corners of the shadow box will be reinforced, see Fig. 1.

Mounting slots 68 are provided in sections 30 to receive edge 69 of mounting flange 38 and locate it in perpendicular relation to end walls 16, see Figs. 2 and 5. Additional bracket mounting slots such as 70 and 72 may be provided in the bottom wall 12 and sections 24. When the shadow box is assembled these slots are aligned in spaced parallel rows and are adapted to receive the edges of auxiliary mounting brackets such as 74 which may be separately formed, see Fig. 1.

To assemble the shadow box, the side and end walls 14 and 16 are initially bent perpendicular to the back wall 12. Then as seen in Fig. 6, the reinforcing members 34 are bent perpendicular to the side walls 14 so that they are coextensive with the inner surface of end walls 16. Next sections 22, 24 and 26 are bent inwardly on score lines 21, 25 and 27, as seen in Fig. 7. These sections are bent still more as seen in Fig. 8 until locking flanges 50 are in parallel coextensive engagement with

the reinforcing members 34. Sections 24 and 26 are then bent still further as seen in Fig. 9 carrying with them the positioning flange 50. It is understood that both sides of the blank are folded this way at the same time.

Next as seen in Fig. 10, sections 28, 30 and 32 are bent on score lines 29, 31 and 33. At the same time sections 60 and 62 of the locking flanges 58 are bent on score lines 59 and 61 as shown. Sections 24 and 26 and sections 28, 30 and 32 are bent still further as shown in Fig. 11 with the free edge of section 32 inwardly spaced from the inner surface of the reinforcing member 34 and the locking flange 50. Sections 24 and 26 along with sections 28, 30 and 32 are bent still further as shown in Fig. 12 with the locking tabs 58 moving temporarily into a position substantially parallel to the back wall 12 and the side wall 14. Further, folding of sections 24 and 26 and sections 28, 30 and 32 bring sections 26 and 32 into coincidence with the inner surfaces of the side and end walls 14 and 16. In this position trapezoidal sections 28 will extend inwardly from the periphery of the shadow box and will overlap sections 22 giving all the frame members a trapezoidal appearance. In addition second sections 24 and 30 of the side and end frame members will extend inwardly toward the end and side walls and towards the bottom wall 12. This arrangement defines a frame member which is triangular in cross section and results in a shadow box which is capable of supporting heavy articles. Furthermore, the edge 54 of locking flanges 50 will bear against the corner edge 56 of the back wall 12. Then as stated above finger 55 is bent back and is embraced by the locking tab 36 which is then in interlocking engagement with the locking flange 50 and holds the frame member 18 in the position described above. Frame members 20 are held in position by forcing the section 60 of the locking members 58 against the inner surface 24 of the frame member 18 and then forcing section 62 into frictional engagement with the side wall 14 with its edge 64 bearing against edge 66 of the back wall.

It should be noted also that frame members 18, 18, 20 and 20 comprise closed-loop triangles, i.e. the sections of the triangular frame members are return bent as indicated so that the remote ends of sections 26, 26, 32 and 32 lie respectively adjacent the remote ends of side walls 14, 14 and end walls 16, 16. This closed loop structure increases the area of the frictional bearing forces of the frame sections and thus, in combination with the above-described locking members, insures the permanent maintenance of the shadow box in assembled relationship without necessitating the use of any independent fastening means such as clips, staples, glue, and the like.

It is believed that my invention, its mode of construction and assembly, and many of its advantages should be readily understood from the foregoing without further description, and it should also be manifest that while preferred embodiment of the invention has been shown and described for illustrative purposes, the structural details are nevertheless capable of wide variation within the purview of my invention as defined in the appended claims.

What I claim and desire to secure by Letters Patent of the United States is:

1. A shadow box formed entirely of sheet material from a single unitary blank comprising a back wall and side walls integral with said back wall, said side walls having opposed ends, one end secured to said back wall, frame members integral with the opposite end of said side walls, each of said frame members comprising a first section having opposed ends, one end integral with said opposite end of one of said side walls and inwardly projecting from the periphery of the shadow box towards said back wall, the opposite end integral with one of the opposed edges of a second section, said second section projecting back toward said one side wall and toward said back wall, the opposite edge of said second section

engaging said one side wall and connected to one of the opposed edges of a third section, said third section in face contact with the inner surface of said one side wall and terminating in butting contact with said first section forming thereby a frame member substantially triangular in cross section, said frame member sections being dimensioned so that the opposite edge of said second section is appreciably spaced from said back wall, and sheet material locking members, said sheet material locking members comprising projections integral with said side walls and with the sections of said frame members, said sheet material locking members adapted to be in interlocking engagement with each other and engaging the side walls and frame members for holding the shadow box in assembled relation.

2. A shadow box formed entirely of sheet material from a single unitary sheet material blank comprising a rectangular back wall and perpendicular rectangular side and end walls secured at one end thereto, substantially rectangular reinforcing members integral with the sides of said side walls and having a locking tab integrally formed thereon, said reinforcing members bent to coincide with the inner surface of said end walls to reinforce them, spaced parallel side frame members integral with the opposite end of said side walls, remote from said back wall, each of said side frame members comprising first, second and third rectangular sections, said first section inwardly projecting from the periphery of the shadow box towards said back wall, said first section having one end integral with said opposite end of said side wall remote from said back wall, and having the other end integral with one of the opposed edges of said second rectangular section, said second rectangular section projecting back towards said one side wall and said back wall and including locking members integrally connected to its opposed sides, said locking members in face contact with the inner surface of the reinforcing members on the inner surface of said end walls, the opposite end of said second rectangular section engaging said one side wall and integral with one of the opposed edges of said third rectangular section, said third rectangular section in face contact with the inner surface of said one side wall to reinforce it and terminating in butting contact with said first rectangular section forming thereby a frame member substantially triangular in cross section, said frame member sections being dimensioned so that the opposite edge of said second section is appreciably spaced from said back wall, said locking members on said second section in interlocking engagement with said locking tabs on said reinforcing members whereby said side frame members are held in position, spaced parallel end frame members perpendicular to and over-lapping said side frame members, said end frame members integral with the opposite end of said end walls remote from said back wall, each of said frame members comprising a trapezoidally shaped first section and rectangular section and third sections, said trapezoidally shaped first section having opposed ends, said trapezoidally shaped first section having its large end integral with the portion of said end wall remote from said back wall and projecting inwardly from the periphery of said shadow box towards said back wall, the opposite edge of said first trapezoidal-shaped section integral with one of the opposed ends of the rectangular second section, said rectangular second section projecting back towards said one end wall and said back wall, said second section including end locking members integrally connected to its opposite sides, the opposite end of said second section engaging said end wall and integral with one of the opposed ends of the rectangular third section, said rectangular third section in face contact with the inner surface of said one end wall to reinforce it and terminating in butting contact with said first trapezoidal-shaped section forming thereby an end frame member substantially triangular in cross section, said frame member sections being dimensioned so

that the opposite edge of said second section is appreciably spaced from said back wall, one portion of said end locking members on said second section of said end frame member coincident with said second section of said side frame member, and the other portion of said end locking member coincident with and reinforcing the inner surface of said side wall to hold said shadow box in assembled relation and to reinforce the corners thereof.

3. A flat sheet material blank for use in making a shadow box, said blank comprising a centrally positioned rectangular back wall section, rectangular side and end wall sections connected to the sides of said rectangular back wall section and separated therefrom by score lines, first, second, and third rectangular shaped side frame member sections connected to the end of said side walls remote from said back wall and separated from each other by score lines, first, second and third end frame member sections, said first section trapezoidal shaped and connected at its large end to the end of said end wall remote from said back wall, said second and third end frame member sections substantially rectangular in shape and separated from each other by score lines, combination reinforcing-locking-bracket mounting member sections connected to said side walls, and combination reinforcing and locking member sections connected to said second frame member sections.

4. A flat sheet material blank for use in making a shadow box, said blank comprising a centrally positioned rectangular back wall section, rectangular side and end wall sections connected to the sides of said rectangular back wall section and separated therefrom by score lines, substantially rectangular reinforcing member sections connected to the opposite sides of said side walls and separated therefrom by score lines, said reinforcing member section having a recess at one side defining a stop edge and including a locking tab separated from said reinforcing member section by a score line, first, second, and third rectangularly shaped side frame member sections connected in sequence to the end of said side walls remote from said back wall and separated from each other by score lines, aligning tabs connected to the opposite sides of said first section of the side frame member sections, substantially rectangular locking member sections connected to the sides of the second section of the side frame member and separated therefrom by score lines, said locking members terminating in fingers, first, second, and third end frame member sections, said first section trapezoidal-shaped and connected by a score line at its large end to the end of said end wall remote from said back wall, said second and third end frame member sections substantially rectangular in shape and connected in sequence by score lines to the opposite end of the trapezoidal-shaped first section, and rectangular locking members connected to the sides of said second section of the end frame member sections and separated therefrom by score lines.

5. The blank set forth in claim 4 in which bracket mounting sections are integral with said reinforcing member sections and separated therefrom by score lines, and each of said second end frame member sections is formed with mounting slots for said bracket mounting sections, said bracket mounting sections being substantially rectangular in shape and having an opening therethrough.

6. A shadow box formed entirely of sheet material from a single unitary blank comprising a back wall, a pair of side walls projecting perpendicularly from said back wall, a pair of end walls projecting perpendicularly from said back wall, closed-loop frame members of triangular cross-section projecting inwardly and peripherally from the remote end of said side walls and end walls, said frame members including inwardly projecting outer panels, said last named panels being inwardly inclined with respect to said back wall, outwardly projecting inner panels and base panels integral with and extending from said inner panels and terminating in butting contact with

said outer panels, said base panels being in face contact with said side walls and end walls, said inwardly projecting frame members being spaced appreciably from said back wall, and locking members securing said side walls, end walls and frame members in assembled position comprising projections integral with said inner panels and side walls, pairs of said locking members inter-locking with each other and all of said locking members coacting with said side walls and end walls for holding the shadow box in assembled relation and spacing said closed-loop frame members from said back wall.
